UNITED STATES PATENT OFFICE.

SMITH MADISON JOHNSON, OF MIDDLEFIELD, OHIO.

CONTAINER.

Application filed May 5, 1924. Serial No. 711,078.

This invention relates in general to containers, and more particularly to that type of container especially designed for use as a paint pail.

- 5 The object of the invention is to provide a container of this character having a body portion of substantially uniform cross section so as to present what is known in the trade as a straight side drum, a feature of 10 importance and advantage in handling as well as in printing labels, descriptive matter or the like on the container, and also being so constituted and organized that the containers may be stacked when either empty 15 or filled in such manner as to present a well balanced and stable column, the containers being also so constructed as to be sealed against the ingress of dust and foreign matter when empty and stacked.
- 20 A further object is to provide a container of this character and having these advantages and capacities and which is also of simple, durable and practical construction and adapted to be manufactured at a com- 25 paratively slight expense from material and by means of facilities ordinarily available.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

35 Figure 1 is a view, partly in section and partly in elevation, showing the containers embodying the present invention as they appear when empty and stacked; and

40 Figure 2 is a view similar to Figure 1, showing how filled containers are stacked.

Referring to the drawings it will be seen that the container constituting the present invention comprises a body portion 5 of substantially uniform cross section and preferably cylindrical. All of the parts of the container are preferably constructed of steel or other suitable metal or material having the requisite resiliency and other properties. The lower end of the container is reduced 45 and presents a reduced and depending annular flange 6 to which a bottom 7 is applied. Of course the bottom 7 is of smaller diameter than the diameter 5 of the cylinder due to the fact that the lower end of the body portion which is constituted by the annular

flange 6 is smaller than the body portion proper. An annular outwardly extending rounded corrugation 8 is formed in the body portion 5 adjacent its lower end and contiguous with the flange 6. This corrugation 60 8 merges into the bottom 7 and by eliminating sharp angles between the bottom 7 and the body portion of the container facilitates the removal of all of the material from the container. 65

The upper end of the container is formed with a rim 9 and below the rim 9 and slightly spaced therefrom an annular inwardly directed rib or shoulder 10 is provided.

The containers as thus constituted are 70 adapted to be stacked when empty and when so stacked present the arrangement shown in Figure 1 with the reduced lower end of one container fitting into the upper open end of the next lower container, the outwardly 75 directed corrugation 8 engaging the rim 9 at all points around the same to support the upper container on the lower and also to keep out dust. A proper bearing of the corrugation 8 on the rim 9 is insured by the 80 action of the rib or shoulder 10 which contacts with the lower end of the upper container to properly center the containers and align their axes. In this manner the containers when stacked provide a stable and 85 well balanced column not liable to be tipped over and also adapted to be economical in the use of storage or shipping space. Moreover the containers when stacked in this manner are effectively and doubly sealed 90 against the ingress of dust and foreign matter, a great advantage to paint companies.

When the containers are filled tops designated generally at 12, are applied thereto. The tops 12 include disk like body portions 13 set into the top of the container and having peripheral attaching flanges 14 designed to be engaged with the rims 9 and spun thereto. By setting the body portions 13 of the top down in the containers, as 100 shown in the drawings they are designed to accommodate and receive the reduced lower ends of similar containers as shown in Figure 2. Thus even when filled the containers may be stacked in a well balanced and stable 105 column for the lower edge of the bottom of the upper container rests on the top 12 while the periphery of the bottom of the upper container is engaged with a shoulder 15 presented by the top 12 where it is united 110

to the rim 9 so as to eliminate play between adjacent containers and prevent one container from sliding off of the other.

I claim:

- 5 1. A container comprising a cylindrical body portion having its lower end reduced and also having an outwardly directed rounded corrugation contiguous with said reduced end, the upper end of the container 10 being designed to receive the reduced lower end of a similar container and said upper end having a rim adapted to engage and support the outwardly directed corrugation of a similar container, the body portion having 15 an inwardly directed and inclined centering rib adjacent and below the rim and adapted to directly engage and coact with the reduced end of a similar container to center the containers when stacked and to

insure an even bearing and close contact 20 of the corrugation on the rim for the entire circumferential extent of the corrugation and rim whereby to exclude dust from the stacked containers as well as to provide a stable stack.

25

2. A container comprising a cylindrical body portion having a flared upper end and a reduced lower end presenting a depending flange, a bottom set in the body portion and secured to the depending flange by a rolled joint, the said flared upper end having an inwardly offset top secured thereto by a rolled joint, said top presenting an annular shoulder adapted to receive and support the rolled joint lower edge of a similar container 30 and center the same in stacked relation.
